US00D927620S

(12) **United States Design Patent** (10) **Patent No.:** **US D927,620 S**
(45) **Date of Patent:** **** Aug. 10, 2021**

(54) **GOLF CLUB HEAD**

(71) Applicant: **PARSONS XTREME GOLF, LLC**,
Scottsdale, AZ (US)

(72) Inventors: **Michael R. Nicolette**, Scottsdale, AZ
(US); **Bradley D. Schweigert**, Cave
Creek, AZ (US)

(73) Assignee: **PARSONS XTREME GOLF, LLC**,
Scottsdale, AZ (US)

(**) Term: **15 Years**

(21) Appl. No.: **29/712,736**

(22) Filed: **Nov. 11, 2019**

Related U.S. Application Data

(63) Continuation-in-part of application No. 29/700,964,
filed on Aug. 7, 2019, now abandoned, and a
continuation-in-part of application No. 29/695,080,
filed on Jun. 14, 2019, now abandoned.

(57) **CLAIM**

The ornamental design for a golf club head, as shown and
described.

DESCRIPTION

FIG. 1 is a top perspective view of a golf club head;
FIG. 2 is a bottom perspective view of the golf club head of
FIG. 1;

FIG. 3 is a front elevational view of the golf club head of
FIG. 1;

FIG. 4 is a rear elevational view of the golf club head of FIG.
1;

FIG. 5 is a top view of the golf club head of FIG. 1;
FIG. 6 is a bottom view of the golf club head of FIG. 1;

FIG. 7 is a left side view of the golf club head of FIG. 1;
FIG. 8 is a right side view of the golf club head of FIG. 1;
FIG. 9 is a top perspective view of a second embodiment of
the golf club head;

FIG. 10 is a bottom perspective view of the golf club head
of FIG. 9;

FIG. 11 is a front elevational view of the golf club head of
FIG. 9;

FIG. 12 is a rear elevational view of the golf club head of
FIG. 9;

FIG. 13 is a top view of the golf club head of FIG. 9;
FIG. 14 is a bottom view of the golf club head of FIG. 9;
FIG. 15 is a left side view of the golf club head of FIG. 9;
and,

FIG. 16 is a right side view of the golf club head of FIG. 9.
The broken lines shown form no part of the claimed design.

1 Claim, 8 Drawing Sheets
